(57) **CLAIM**

The ornamental design for a disposable tattoo handgrip, as shown and described.

DESCRIPTION

FIG. 1 is a top plan view of the disposable tattoo handgrip of the claimed design;

FIG. 2 is a bottom plan view of the disposable tattoo handgrip;

FIG. 3 is a front view of the disposable tattoo handgrip;

FIG. 4 is a rear view of the disposable tattoo handgrip;

FIG. 5 is a right side view of the disposable tattoo handgrip;

FIG. 6 is a left side view of the disposable tattoo handgrip;

FIG. 7 is a top/left/front perspective view of the disposable tattoo handgrip;

FIG. 8 is a top/right/front perspective view of the disposable tattoo handgrip;

FIG. 9 is a bottom/left/rear perspective view of the disposable tattoo handgrip;

FIG. 10 is a bottom/right/rear perspective view of the disposable tattoo handgrip; and,

FIG. 11 is a front view of the disposable tattoo handgrip shown in a use state.

The broken lines shown a human hand in FIG. 11 is included for the purpose of illustrating environmental structure and forms no part of the claimed design.
